UNITED STATES PATENT OFFICE

WALTER A. SAATMAN, OF ROSLYN, PENNSYLVANIA

TURRET-BOX MACHINE

Application filed August 6, 1926. Serial No. 127,551.

My invention relates to an automatic box wrapping machine.

A purpose of my invention is to apply a wrap to the sides and ends of a box while it is upon a form carried by a turret.

A further purpose is to apply a wrap to the bottom of a box by the rolling motion of a turret, presenting the wrap glue side out upon a registry roll by the engagement between the wrap and the bottom of the box carried by the moving turret.

A further purpose is to mount box forms upon the arms of a three-way turret to feed unwrapped boxes to the forms at the present position of dwell, to apply a wrap to one edge of the bottom of the box on each form in its second position of dwell, to transfer a wrap to the bottom of the box by rolling motion of the turret as the turret moves from second to third position of dwell, and to wrap up the sides and ends of the box in the third position of dwell. I preferably apply a shut down safety device between the first and second position.

A further purpose is to position a registry or wrap-delivery roll, to resiliently press a wrap wound upon the roll against the bottom of a box on a form carried by a turret during a dwell of the turret and during the next movement of the turret to unwind the wrap to the bottom of the box in rotating the roll by its resilient engagement with the bottom of the box.

A further purpose is to apply boxes of variant size to a turret so that the bottoms and forward ends of the boxes are in the same position irrespective of variation in size of box, and to register box wraps upon a wrap-delivery roll in respect to the unchanging position of the line of intersection between the bottoms and forward ends of the respective boxes during one position of dwell of the turret, and to register one end of end- and side-wrapping mechanism, commonly called "side-wrapping" mechanism in the unchanging plane of the forward sides or ends of the boxes during another position of dwell of the turret.

A further purpose is to mount a wrap gripper and a registry roll upon a common

axis, synchronizing the gripper to take hold of an approaching wrap to turn the gripper and registry roll as a unit to definite registered stop so as to register the wrap with the bottom of a box upon a form carried by a turret.

A further purpose is to mount a registry roll to swing about its driving shaft and to provide it with a wrap gripper on arms adapted to turn around the axis of the roll.

A further purpose is to accommodate differences in box depth by adjusting the angular position of the arms of a gripper with respect to the dwell of a driven intermittent gear driving the arms and to make a corresponding reverse adjustment in the angular position of the driving intermittent gear in order to maintain the position of gripping unchanged.

A further purpose is to avoid engagement between a glued wrap and any form that does not carry a box by automatically shutting down the mechanism presenting the wrap and the feed of wraps to the mechanism.

A further purpose is to provide grippers that extend out to grab an incoming wrap, then move down to the circumference of a registry roll, and travel around with the registry roll to a definite stop and to vary the position of the stop according to the depth of the box.

A further purpose is to apply drag fingers to the wrap upon the registry roll to maintain the wrap upon the roll.

A further purpose is to mount box forms upon hollow arms and to operate box grippers through the hollow arms.

A further purpose is to support box forms upon offset turret arms.

A further purpose is to wrap corner-laps with continuous rotary motion, preferably using a notched disc bevelled at the notch.

A further purpose is to turn in the tops of the wraps over the box by reaching inside the box and pulling outwardly against pressure blocks outside of the box.

A further purpose is to mount a side wrapping unit to operate with continuous crank motion and, in one position of dwell of a

turret carrying a box upon a form, to raise the wrapping unit brushing and rolling up the long sides, turning the corner laps and brushing and rolling up the short sides.

5 A further purpose is to strip the box from a form carried by a turret and support the box, all during the downward stroke of side wrapping mechanism, and during the continuing down stroke of the mechanism to 10 turn in the upper edges of the wrap over the sides of the box.

A further purpose is to strip the box from its form, after applying the wrap over the sides of the box, by means of rods vertically 15 descending in or through perforations in the form upon each side of the turret.

A further purpose is to apply turn-in clamp mechanism throughout a portion of the down stroke of side wrapping mechanism 20 and throughout a portion of the next up stroke of the mechanism.

A further purpose is to push a wrapped box to a delivery belt or point by its engagement with the next box.

25 A further purpose is to carry brushes, rolls, corner-lap and turn-in mechanism upon a vertically moving carriage comprising front and rear carriers and side carriers, adjusting for change in width of box by rearward 30 and forward adjustment of the rear carrier and adjusting for change in length of box by lateral adjustment of the side carriers.

A further purpose is to automatically adjust the lateral brushes of a side wrapping 35 unit about half way between the front and rear brushes so that the high bristles engage the middle of the short sides of a box.

A further purpose is to operate the corner-lap and turn-in mechanism of side wrapping 40 mechanism by the vertical motion of a carrier of the mechanism.

A further purpose is automatically to maintain resilient pressure upon the side roll central with respect to the box.

45 A further purpose is to make offsetting adjustment in a crank operating the vertical movement of side wrapping mechanism in order to adapt the mechanism to operate upon boxes of different depths.

50 A further purpose is to operate turn-in and box support mechanism from the same shaft, preferably operating the box support mechanism near the dead center of the turn-in mechanism.

55 A further purpose is to spring-counter-weight side wrapping mechanism and to increase the arm of the spring as the mechanism moves up and the spring weakens from extension.

60 A further purpose is to adapt inner turn-in members to variant box dimensions and to removably support the turn-in mechanism to facilitate adaptation to different sizes of box.

65 A further purpose is to mount a turret upon

a hollow shaft and to operate box strippers by means of a shaft through the turret shaft.

A further purpose is to perforate a box form to receive a threaded turret arm and to removably clamp the form to the arm 70 between a pivoted cross bar and a nut carried by the arm, the cross bar being pivoted to the end of the arm and adapted to turn axially into position to pass through the perforation. 75

A further purpose is to provide for small screw adjustments of a form to secure exact registry between the form and the surface of a wrap-applying roll.

Further purposes will appear in the specification and claims. 80

I have preferred to illustrate my invention by one form only, but have selected a form which is efficient and practical in operation and which illustrates particularly well 85 the principles involved.

Figure 1 is a diagrammatic elevation to illustrate the cycle of operation.

Figure 2 is a broken left side elevation with some parts removed. 90

Figure 2^a is a fragmentary detail section taken upon the line 2^a—2^a of Figure 2 to illustrate a detail of operating mechanism of the box support rods.

Figure 3 is a fragmentary section taken upon 95 the line 3—3 of Figure 2 in the direction of the arrows.

Figure 4 is a broken right side elevation.

Figure 5 is a fragmentary section taken on the line 5—5 of Figure 4 illustrating cam 100 and clutch mechanism.

Figure 6 is a front elevation.

Figure 7 is a section of Figure 6 taken upon the line 7—7 in the direction of the arrows. 105

Figures 7^a and 7^b are fragmentary detail views of gripper mechanism and are respectively a top plan view and a vertical section upon the line 7^b—7^b of Fig. 7^a.

Figure 8 is a top plan view with some parts 110 removed.

Figure 9 is a fragmentary section to enlarged scale taken upon 9—9 of Figure 8.

Figure 10 is a fragmentary section to enlarged scale on line 10—10 of Figure 8, or 115 10—10 of Figure 6, being a continuation of structure shown in Figure 9.

Figure 11 is a right end elevation of structure shown in Figure 10.

Figure 12 is a section to enlarged scale 120 taken upon the line 12—12 of Figure 6, with the back carrier moved forward.

Figure 13 is a fragmentary section taken upon the line 13—13 of Figure 12.

Figure 14 is a section of Figure 6 upon 125 the line 14—14.

Figure 15 is a section taken upon the line 15—15 of Figure 12, to the same scale as Figure 12, but not showing the front carrier.

Figure 16 is an elevation of a turn-in disc. 130

Figure 17 is a broken section to enlarged scale taken upon the line 17—17 of Figure 2.

Figure 18 is a section taken upon the line 18—18 of Figure 17 to show left-hand operating mechanism of the gripper and operating mechanism of the drag fingers.

Figure 19 is a section upon the line 19—19 of Figure 17 illustrating the right-hand operating structure of the gripper.

Figure 20 is a section on the line 20—20 of Figure 17 showing structure for angular adjustment of the gripper arm.

Figure 21 is an opposite or left hand view to enlarged scale of the safety automatic clutch mechanism, shown dotted in Figure 4, being a section upon the line 21—21 of Figure 22.

Figure 22 is a section on the line 22—22 of Figure 21.

Figures 23 and 24 are diagrammatic sectional plans taken upon the lines 23—23 and 24—24 respectively of Figure 7 with parts removed for greater clearness.

Figure 25 is a left end view of Figure 24.

Figure 26 is a detail section taken upon the line 26—26 of Figure 13 illustrating the structure for automatic adjustment of the side brushes and of a spring support of the side brushes as well as structure of the corner-lap discs.

Figure 27 is a diagrammatic elevation showing turn-in clamp structure, corresponding to a section upon the line 27—27 of Figure 28.

Figure 28 is a fragmentary diagrammatic section taken upon the line 28—28 of Figure 27 and of reduced scale.

Figure 29 is a diagrammatic detail plan illustrating the resiliently balanced support of the side rolls.

Like numerals refer to like parts in all figures.

Referring to the figures and describing in illustration and not in limitation:—

Supporting structures and driving mechanisms may be widely varied without departing from my invention and for this reason as well as for greater clearness I have omitted such structures and mechanisms.

Here a suction roll 40 delivers a wrap from a suitable pile of wraps 41 to the gripper 42 on the main cylinder 43 of the glue machine.

The main cylinder of the glue machine, turning in the direction of the arrow carries the wrap, held to place by the gripper 42, past the rider wheel 44 and delivers it to the picker plate 45 which guides it to the glue-applying roll 46.

The glue-applying roll is maintained uniformly coated with glue as by means of a dip roll 47 dipping into a glue pot 48 and engaging a transfer roll 49 that in turn engages the glue-applying roll. A squeeze roll 50 engaging the surface of the glue-applying

roll after it has passed the transfer roll smooths out the glue upon the glue-applying roll, in a manner well understood and not relevant to the present invention.

The wrap received by the glue-applying roll from the picker plate 45 is removed from the glue-applying roll by suitable strippers 51 which guide it into the open jaws of a gripper 52.

This gripper, is swinging clockwise upon an arm 53 when it receives the wrap, for the time moving as one with the registry or wrap-applying roll 54 about the axis of the registry roll and is synchronized to seize the edge of the approaching wrap, turning inwardly on its own axis anti-clockwise to bring the edge of the wrap to the surface of the roll while continuing its travel as one with the roll around the roll axis.

As the gripper 52 passes beneath drag fingers 55 which are spaced along a shaft 56, these drag fingers move down and resiliently engage the wrap behind the gripper.

The arm 53, the gripper 52 carried by the arm and the registry roll 54 move around as a unit to a definite stop and then stop as a unit in position to register the wrap with the bottom of a box 57 upon one of the box forms 58 carried by the turret 59.

After coming to a stop the registry roll 54 swings to the right upon a rocker arm 60 about pivot 61 under the action of a spring 62 which resiliently maintains roller engagement at 63 between the rocker arm and a cam 64 which is conveniently carried upon the shaft 65 of the main cylinder 43 of the glue machine.

This motion to the right loosens the fastening between the gripper arm 53 and the registry roll 54 and continues until the registry roll engages the lower corner 66 of the box 57 upon one of the forms 58 of the turret. The turret is stationary at the moment of engagement with the registry roll, but after engagement starts to move in the direction of the arrow to its next position, making rolling engagement with the registry roll upon the glued surface of the wrap, the registry roll being now free to turn upon its shaft 67 without affecting the position of the gripper arm 53.

After the registry roll has swung over into contact with the box upon the form 58 the gripper 52 loosens its hold upon the wrap and the form of the cam 64 is such that the rolling surface of the registry roll maintains resilient pressure against the bottom of the box carried upon the form, rolling the glued wrap upon the bottom of the box, and maintaining a uniform slight clearance between the roller and cam at 63.

The box is shown held in place on its form by a box gripper 68 which makes gripping engagement with the box, clamping the box to the form as soon as the box has left the reg-

istry roll. These grippers may be operated by a suitable cam 69 mounted on a sleeve upon the shaft of the turret, and when used loosen and move out of the way in time to avoid engaging the wrap during the wrapping operation.

The turret in moving to the next dwell brings the box to rest in the third position in which the box is presented vertically to the wrapping mechanism which now moves upwardly to wrap up the sides while the box is still on its form.

As the wrapping mechanism moves upwardly the long-side brushes 70 followed by the rolls 71, sweep up the long sides of the box front and rear and the corner-lap discs 72 follow turning in the edges of the wrap around the ends of the box.

The corner-lap discs are followed by the short-side brushes 73 and the short-side rolls 74, all of this while the box is upon the stationary form 58 carried by the turret.

The wrapping mechanism moves upwardly until the pressure blocks 79 are at the top of the box when the supporting rods 77 move underneath the box and the stripper rods 75, which have been moving downwardly through suitable perforations 76 in the box form, come into contact with the bottom of the box and continue to move downwardly with the now downwardly moving wrapping mechanism and supporting rods.

The supporting rods 77 and the whole wrapping mechanism move down with the box strippers 75, the form 58 remaining stationary and the strippers spring-pressing the bottom of the box against the supporting rods.

After the box has been thus stripped from the form the strippers are pulled up through the perforations 76 in the form and the turret moves to its next position.

When the box is clear of the form, turn-in clamps 78 turn in the upper edges of the wrap over the sides of the box and spring-clamp the turned in edges against outside pressure blocks 79 fitting around the box to support the strong clamping pull of the turn-ins 78.

The turn-in clamps loosen and move back, out of the box before the wrapping mechanism engages the next box, which engages and pushes away the box already wrapped to fall upon a suitable belt conveyor 80 for delivery to any suitable receptacle, the supporting rods 77 moving out of the way to permit delivery of the wrapped box.

During each period of dwell of the turret, the form on first position (at the right) receives an unwrapped box from an operator, a box on the form in second position (at the left) is engaged by a glued wrap upon the registry roll, and a wrap upon the bottom of the box on the form in third position (in the middle) is applied up the sides of the box and the box is then stripped from its form.

During each turning movement of the tur-

ret from dwell to dwell, a safety shut-down lever 81 engages the bottom of the box carried by the form passing from first position to second position to prevent an automatic shut down of mechanism operating the registry roll and the feed of additional wraps. If this form does not carry a box, an engagement between the glued wrap upon the registry roll and the empty form in its next position of dwell is avoided and the feed of additional wraps is stopped.

The rolling engagement between the bottom of the box carried on the form moving from second to third position of dwell and the glued surface of the wrap on the registry roll applies this wrap to the bottom of the box.

If a box gripper 68 is used it will normally operate to clamp the box to the form as the box leaves the registry roll and to open and move out of the way during the next period of dwell.

The unwrapped boxes are applied to the successive box forms at the first position of dwell, the unglued wraps picked up automatically from a pile 41 are successively rolled on to the bottoms of the boxes by the registry roll pressed against and turned by the box bottoms, the sides are automatically wrapped and the turn-ins around the top are automatically effected by vertical up and down movement of mechanism beneath the third position of dwell and the finished boxes are delivered by the belt conveyor 80.

I now describe the structure illustrated in Figures 2 to 27 which embodies my invention in a particularly advantageous form.

Frame

The main frame (Figures 2, 4, 6, 7 and 8) is shown as comprising right and left sides 82 and 83 respectively. These sides are tied together at the back by feed mechanism not shown, and also by the main driving shaft 84, the shaft 85 of the turret 86, the driving shaft 87 of the registry roll, and the rocker shaft 88 that raises and lowers the carriage 89 of the wrapping mechanism.

The drive

The main driving shaft 84 (Figures 2, 4, 6, 7 and 8) carries a worm gear 90 meshing with a worm 91 on a shaft 92 driven by a motor, not shown, preferably mounted upon the side 82 of the frame.

The shaft 84 carries keyed to it a gear 93 which meshes with a gear 94 mounted upon a stud 95 in the frame member 82. The gear 94 is integral with a Geneva gear 96 and carries a roller 97 upon a pin 98 to drive a Geneva wheel 99.

The shaft 84, gears 93 and 94 and the Geneva gear 96 rotate continuously, resulting in intermittent drive of the Geneva wheel 99.

Integral with the Geneva wheel 99 is a gear 100 which meshes with a gear 101 keyed to

the hollow shaft 85 carrying the turret 86. There is a two to one ratio between the gears 100 and 101 so that the six-way Geneva wheel gives three-way drive to the turret.

5 The gear 94 which is continuously driven by the gear 93 has clutch connection with a gear 102 which is in driving mesh with a gear 103 rigidly mounted on the driving shaft 87 (Figures 4 and 17) of the registry roll and 10 with a gear 104 mounted on the shaft 65 of the main glue cylinder 43.

This clutch connection between the gears 94 and 102 which is automatically disconnected every time one of the box forms 58 on the 15 turret approaches the registry roll if there be no box on the form so that whenever there is no box on an approaching form, the registry driving gear 103 and the driving gear 104 of the main glue cylinder both stop.

20 The main drive shaft 84 extends from side to side of the frame and at one end carries a crank 105 which raises and lowers the carriage 89 of the wrapping mechanism, shoes in the right and left ends 107 and 108, respectively, of the carriage sliding up and down in vertical guides 109 and 110 of the frame structure.

The crank 105 is connected by a link 111 to the crank arm 112 keyed to the rocker shaft 30 88 which extends from side to side of the frame and carries keyed to it arms 113 and 114 that are connected by links 115 and 116 to the respective ends 107 and 108 of the carriage so that the carriage is raised and lowered once 35 for each revolution of the driving shaft 84.

At the right side the driving shaft 84 carries a cam 117 (Figures 4 and 6) to operate the stripper mechanism for stripping off the boxes from the box forms 58, by means of bell 40 crank 118 spring-pressed at 119 into roller engagement at 120 with the cam and operating a link 121 and toothed sector 122 keyed upon a shaft 123 that operates the stripper mechanism.

45 On the left inside of the crank 105 there is a face cam 124 (Figure 2) which oscillates a horizontal link 125 guided at 126 and having a rack 127 at its right-hand end. This rack oscillates a pinion 128 to effect motion 50 of the support rods as described later.

The shaft 84 carries inside the left frame member a cam 129 (Figure 8) which by means of an arm 130 mounted upon the lower end of a vertical shaft 131 (Figure 6) oscillates a toothed sector 132 to operate member 133 which meshes at its other end (by rack) with gear teeth 134 upon a sleeve 135 carrying cam 69 which operates the box grippers 68 (see 60 Figures 6, 8, 9 and 10).

The wrapping mechanism includes brushes, rollers and turn-in clamps at each side and the corner-lap discs at the ends; also the supporting rods which are moved beneath the box 65 before the strippers remove the box from the

form and support the box during the operation of the turn-in clamps.

The mechanical operations include giving proper turn-in and clamping motion to the turn-in clamps and proper motion back and forth to the supporting rods. 70

The corner-lap discs 72 and the turn-in clamps 78 are operated by the up-and-down motion of the carriage in the frame. A vertical rack 136 (Figures 6, 8 and 23) is fastened 75 to the left side of the frame and meshes with a pinion 137 on a shaft 138 which operates the corner-lap discs, driving the shaft 139 of the rearward corner-lap discs through bevel gears 140 and 141 and the shaft 142 of the forward 80 discs through the bevel gears 143 and 144.

The front and rear turn-in clamps are operated by means of a bell crank 145 (Figure 4), carrying a roller 146 rolling in a stationary cam slot 147 in a member 148, fastened to 85 the right side of the frame.

This bell crank 145 carries a bevel sector 149 which meshes with a bevel gear 150 upon the shaft 151 that operate the front and rear turn-in clamps. 90

The right and left side turn-in clamps are operated by a similar bell crank 152 (Figure 2) having a roller 153 rolling in a slot 154 of a cam member 155. The bell crank 152 is pivoted at 156 and carries a toothed sector 95 157 which meshes with a spur pinion 158 keyed to the shaft 159 which operates the side turn-in clamps.

Carriage

100

The carriage 89 is best seen in diagrammatic Figures 23 to 26 taken in combination with Figures 2, 4, 6 and 7.

It comprises right and left end plates 107 and 108 tied together by the front and rear tie rods 160 and 161 at the ends, by the front and stationary carrier 162 and to lesser extent by the transverse shaft 159 operating the side turn-ins, the transverse shaft 163 cross connecting the screw shafts 164 and 165 and the rear carrier 166. 105

Each end plate extends upwardly at the rear end to journal the transverse shaft 163 at 167 and to provide end bearing at 168 for one of the screw shafts 164 and 165. 110

Each plate extends upwardly near the front to receive a projection pin or lug 169 in the adjoining end of the front and stationary carrier 162.

The left-hand end plate 108 carries the 120 stud 156 supporting the bell crank sector 152 for operating the side turn-ins and the support rods, while the right-hand plate carries the stud 170 which supports the bell crank 145 operating the front and rear turn-in clamps. 125

The apron or front and stationary carrier 162 is provided with spaced brackets 172 (Figure 12) carrying the front roller, and also carries the bearings 173 and 174 (Figure 130

23) supporting the shaft 142 carrying the forward corner-lap discs which are splined on the shaft 142 and positioned along the shaft by the respective side carriers 175 and 176 (Figure 6).

5 In the middle in front at 177 (Figures 23 and 24) the apron also supports mechanism of the front and stationary turn-in clamp 78.

The right and left side carriers 175 and 176 (Figure 6) are counterparts, and are mounted at 179 and 180 between and by rack and pinion adjustment slide along the tie rod members 160 and 161 (Figures 2, 4, 7, 12 and 14). A shaft 181 (Figures 12 and 26) having opposite ends journaled at 182 and 183 (Figure 26) in the carrier carries pinions 184 (Figure 14) meshing in rack teeth 186 upon the respective tie rods, and a handle 187 for rolling the carrier along the tie rods.

20 The rear carrier 166 is adjustable forward and rearward along the screws 165 and 164 which have bevel gear connection at 188 and 189 with the cross shaft 163 and operate together by a handle 190.

25 The rear carrier slides along the drive shaft 138 of the corner-lap discs and along the drive shaft 151 of the front and rear turn-ins. It supports the splined shaft 139 carrying the rearward corner-lap discs in bearings 192 and 193 (Figure 23) and also houses and positions along the shaft 138 the beveled gear 140 which drives the shaft 139.

The turret

35 The turret 59 is best seen in Figures 1, 4, 6, 7, 8, 9 and 10. The body of the turret is keyed to the hollow shaft 85 which journals in the sides 82 and 83 of the frame and carries fastened to it the gear 101 (Figures 4 and 8) that is driven by the gear 100 fastened to the six-way Geneva wheel 99, which is already described by the driving shaft 84.

40 Each revolution of the main driving shaft 84 turns the Geneva wheel one-sixth of a revolution and there being two to one ratio between the gears 100 and 101 turns the turret one-third of a revolution.

The turret is provided with three arms 194 uniformly spaced around the body of the turret. These arms are axially offset from the axis of the turn table in order to make perpendicular engagement with the box forms 58 near the forward sides 58' (Figure 1) of the forms, and they preferably comprise forwardly slotted tubes fastened into the arm portions 195 of the body of the turret, and adapted to removably hold box forms of different size. Obviously more turret arms would require corresponding difference in the "ways" of the geneva.

45 The tubular arm is shown to enlarged scale in Figures 10 and 11. The tube 196 is slotted for some distance from its end and carries pivoted at its outer end at 197 a cross member 198 which is adapted to turn in line with the

tube, one side 199 of the cross bar passing into the slot 200 of the tube.

The upper surface of the cross bar 198 is preferably half round or curved to fit the half round or curved groove 201 in the bottom of the form and may also fit the inside of the tube 196. The cross bar when clamping a form fits the groove 201 and presents a flat bottom 202 even with the surface of the bottom of the form.

75 After the arm has been inserted and the cross bar turned perpendicular the form is clamped to place by screwing down upon a suitable nut 203.

A very slight adjustment is provided to 80 permit exact registry between a form that may not be quite true and the registry roll.

A washer 204 next to the box form carries a short pin 205 on each side of the tubular arm 196. Each pin is shown held to place by 85 a screw 206.

An upper washer or sleeve member 207 houses the pins 205 at 208 and is laterally extended at 209 and 210. Set screws 211 and 212 are provided in these lateral extensions 90 and the form may be slightly adjusted angularly to exactly register with the surface of the registry roll by relative adjustment of these screws.

Registry roll

95

The registry roll mechanism is best seen in Figures 2, 4, 7 and 17. The roll 54 is mounted between relatively rigid arms 60 and 60' to receive a glued wrap at the glue-applying roll and subsequently to swing over into position for presenting it to a box on a temporarily stationary form 58 upon the turret.

The arm 213, shown diagrammatically in Figures 1 and 4, extends downwardly to present the roller 63 to engage the outside surface of the cam 64 upon the shaft 65 of the main cylinder of the glue machine. A spring 62 maintains the roller in engagement with the cam. The cam 64 moves synchronously 105 with the motion of the main cylinder of the glue machine and with the operation of the turret permitting the spring 62 to swing the registry roll in against the forward corner 66 of the bottom of a box on the adjacent then stationary form and to maintain the roll 110 against the bottom of the box as the turret moves forward to its next position.

115 During rolling contact of the registry roll upon the bottom of a box on the turret the cam 64 is barely out of contact with the roller 63, and contact makes again between the cam and roller as soon as the box has moved past the roll.

The left-hand arm 60' (Figure 17) 120 comprises a gear casing and has a sleeve portion 214 adapted to turn in the left-hand bearing 215 and keyed at 216 to a sleeve 217 that is rigidly fastened at 218 to the rocker arm 60.

125 At the left-hand end of the shaft two simi-

130

lar intermittent driving gears 219 and 220 are mounted to turn rigidly with the shaft 87.

The inner driven gear 219 is keyed to the shaft 87 and the outer driving gear 220 is 5 angularly adjustable with respect to the shaft being mounted upon a sleeve member 221 which is keyed to the shaft at 222 angularly adjustable with respect to the outer gear at 223.

10 The driven intermittent gears 224 and 225 mate with the gears 219 and 220 respectively and are integral respectively with the gears 226 and 227 that mesh with the gears 228 and 229 and are similar to one another, each with 15 concave stop portion 230 (Figure 2) fitting the convex curvature 231 of the toothless portion of its driving gear 219 or 220 (Figure 17).

The gear 228 is keyed to a sleeve 232 that 20 turns in a bearing 233 on the arm 60' and is flanged beyond the bearing to form a cam 234 for operating the drag fingers.

A cam member 235 is rigidly fastened to the face of the cam 234 by a suitable screw 25 236 for operating the outer jaw of the gripper 52.

The outer gear 229 turns with the shaft 237 and is made angularly adjustable with respect to this shaft by making it angularly 30 adjustable with respect to a sleeve member 238 (like the member 221) that is keyed to the shaft 237. The adjustment is at 239.

The arrangement is such that the inner intermittent driving gear 219 turns the cam 35 members 234 and 235 that operate the drag fingers and the outer jaw of gripper while the outer intermittent driving gear 228 turns the shaft 237 and the arms 240 and 241 which carry the gripper 52.

40 The arms 240 and 241 of the gripper are keyed to the shaft 237 at 242 and 243 and support the gripper in bearings 244 and 245.

The registry roll 54 turns with the shaft 237 so long as a clutch member 246, that turns 45 with the shaft 237 but is slidable along the shaft somewhat, is in engagement with a cooperating clutch member 247 on a hub 248 of the roll 54 but is free to turn upon the shaft when this clutch opens.

50 Opening of the clutch is automatic when the registry roll has swung somewhat toward the turret by reason of cam release of the outer end of a rod 249 pinned at 250 to the clutch member 246 through a slot 251 in the 55 shaft and spring-pressed at 252 against a stationary cam member 253. The spring 252 is compressed between the bottom of a hole 254 in the shaft and the rod 249 fastened to the clutch member. This presses the clutch 60 to release as soon as the end of the rod moves off the cam 253 which takes place when the roll swings over toward the turret, as best seen in Figures 5 and 17.

The gripper 52 (Figures 1, 7, 7^a, 7^b and 17 65 to 19) comprises outer and inner jaws 255

and 256 (Figures 7 and 7^b) that are rigidly connected respectively to an outside tubular member 256' turning in bearings 244 and 245 at the end of the arms 240 and 241 respectively, and to a rod member 259' inside the tube 256' and that carries a pinion 262 (Figures 17 and 18) which meshes with a toothed sector 263. This sector is on a bell crank 264 that is pivoted at 265 to the gripper arm 241 and has an arm 266 carrying a roller 267 which engages the cam member 235, being spring-pressed to engagement by a spring 268.

The tubular inner jaw member presents outwardly bent inner jaw portions 256 at intervals along its length to the blade outer jaw members 255 that are inset in the rod 259. The tubular member carries outside the bearing 244 at its right-hand end a pinion 269 (Figures 17 and 19), and the rod 259 is extended beyond the pinion 269 where it carries a collar 270 as an end bearing.

The pinion 269 meshes with a toothed sector 271 on a bell crank 272 pivoted at 273 to the gripper arm 240 and which carries a roller 274 engaging a stationary cam 275 to operate the inner jaw. A spring 276 maintains the roller in engagement with its cam.

By inner jaw is meant the jaw having teeth adjacent the roll and by outer jaw is meant the jaw having teeth furthest from the roll. The outer jaw member is carried on a rod member inside the sleeve member carrying the outer jaw.

The arms 240 and 241 of the gripper are 100 turned by the outer pair of intermittent gears 220 and 225 and the cams 234 and 235, operating the drag fingers 55 and the opening and closing of the gripper 52, respectively, are operated by the inner pair of intermittent gears 219 and 224. 105

The pairs of intermittent gears are the same, one pair matching the other pair, so far as the teeth are concerned but are set differently. The driving gear 219 is exactly the 110 same as the driving gear 220, and the driven gears 224 and 225 as gears are alike, but the periods of dwell of the driven gears take place at different times and these times are relatively adjustable.

The period of dwell of the driven gear operating the cams is always the same, that is always occurs at the same time with respect to the position of the driving shaft 87 of the registry mechanism, and the cams 235 and 234 operating respectively the opening and closing of the gripper and the operation of the drag-fingers never have to be changed in their positions with respect to the sleeve 232 or to the sleeve 238 after these positions have 115 been once determined.

The opening and closing of the gripper takes place by reason of relative motion between the gripper arms 240, 241 and the cam 255. This can only take place when one of 120 125 130

the pairs of intermittent gears is in its position of dwell and the other pair is rotating.

If the intermittent gears driving the cam are in dwell and the other pair of intermittent gears are rotating the arms of the gripper, then the relative motion between the cam and the roller 267 operating the opening and closing of the gripper is in one direction and when the other pair of intermittent gears is in dwell and the first in motion the relative movement between the roller and its cam is reversed.

There is no relative movement between the gripper arms and cam 235 when both pairs of intermittent gears are turning nor when they are both in dwell.

Cycle

Starting at the closing of the grippers upon a wrap from the glue roll the arms 240 and 241 are at this time rotating, and the cam 235 is in position of dwell.

When the roller 267 rolls up on the cam the outer jaw 255 of gripper closes against the action of its spring, the jaws moving in very near to the surface of the registry roll.

All this time the arms are rotating and the right-hand intermittent gears operating the cams 235 and 234 are in position of dwell.

This dwell must be over before the gripper has moved past the shaft 56 carrying the drag fingers 55 as the drag fingers are operated by rolling engagement between the cam 234 and a roller 277 of a sector 278. The sector 278 is pivoted at 279 to the supporting arm 60' and spring-pressed at 280 to roller engagement with the cam, and meshes with a pinion 281 upon the shaft 56 carrying the drag fingers.

The gripper arms stop rotating when the left-hand intermittent gears reach their position of dwell and at this time the right-hand intermittent gears turning the cams 234 and 235 are out of dwell the driven gears 226 and 228 rotating.

The whole registry mechanism swings over toward the turret carried upon the relatively rigid rocker arms 60 and 60' under the action of the cooperating spring 62 and cam 64, this motion starting at or shortly after the arms carrying the gripper come to rest, and the registry roll is thus brought into engagement with the forward corner of a box upon a stationary form on the turret, the turret being in a position of dwell at the moment of engagement.

Just after engagement between the roll and box, the gripper opens due to the continued motion of the cam 235.

As the registry roll swings out of position near the glue-applying roll the clutch member 246 is released as already explained adapting the registry roll to turn freely with respect to the arms of the grippers.

Some little time after engagement between

the turret and the registry roll the left-hand intermittent gears end their period of dwell and the gripper arms begin again to rotate.

In opening the gripper, the inner jaw 256 positioned by the stationary cam 275 at the right of the registry roll and the opening is effected by moving the outer jaw 255 outwardly away from the surface of the roll by engagement between the cam 235 and its roller 264 upon the sector 263 meshing with the pinion 262 fastened to the outer jaw of the gripper, which is fastened to the internal shaft or rod 259.

The inner gripper jaw 256 is moved outwardly by the stationary cam 275 and co-operating sector 271 to a position to receive a new wrap at any suitable intermediate point between the turret engaging position and the position at which the gripper receives another wrap.

It will be understood that the function of the gripper mechanism is to deliver the successive wraps from the glue roll to the registry roll mechanism for subsequent registered presentation to the bottoms of successive boxes on the turret, a registered presentation adapted to easy and exact adjustment to accommodate boxes of different depths.

The turret starts to move forward to its next position at or shortly after the opening of the gripper jaws.

This rolling of the registry roll because of its engagement by the revolving box bottom is accompanied by a bodily swinging movement of the roll first forward, until the registry roll passes the perpendicular from the axis of the turret to the bottom of the box and then rearward, and the return swinging motion continues by reason of the action of the cam 64 after the registry roll has left the bottom of the box, the registry roll getting back into its original position at or somewhat before the time for gripping a new wrap, which begins a new cycle.

Automatic trip mechanism

This is shown in Figures 4, 21 and 22.

A rocker arm 285 mounted upon a shaft 282 journaled in standards 283 and 284 upon the top of the frame structure has a toe 81 which is adapted to register with slots 286 in each of the box forms 58 upon the turret.

Every time the turret moves a form past the toe 81 of the rocker lever, a clutch member 287 shuts down the operation of the registry roll and the feed of wraps if the toe register with the slot but the clutch member is prevented from operating and shut down is avoided if a box is on the form to cover the slot and engage the toe.

The clutch operates between the gear 94 driven continually by the gear 93 upon the main driving shaft 84 and the coaxial gear 102 which drives the mechanism of the regis-

try roll and the main cylinder of the glue machine.

The clutch member is mounted in the hub 288 of the gear 94 and comprises a pin 289 spring-pressed at 290 to engagement with the gear 102 driving the mechanism of the registry roll and the main cylinder of the glue machine.

The gear 102 has a hole 291 adapted to register once each revolution with the pin 289. The pin has a rack 292 upon one side and a small pinion 293 pivoted within the hub 288, meshes with the pin rack 292 on one side and with a movable rack member 294 upon the other.

The rack member 294 is adapted to slide in and out within a suitable guiding hole 295, and has a sloping end 296 that extends beyond the face 297 of the hub 288 whenever the pin 289 enters the hole 291 in the gear 102.

The pin is adapted to be pulled out against the action of the spring by pushing in the outer end 296 of the rack member 294.

A rocker cam member 298 is pivoted at 299 between the side frame 82 and the hub 288 of the gear 94 and is adapted to swing into position to engage and press on the outer end of the rack member 294 causing the pin 289 to be withdrawn from the hole 291 in gear 102 which stops the operation of the feeding and registering mechanism when no box is present on the form.

If this engagement is effected the rack member 294 is pushed in and the pin 289 is held out against the action of its spring 290 and the clutch engagement between the gears 94 and 102 is open.

The rocking cam member 298 is spring-pressed at 300 to be maintained upon either side of its dead center with respect to the spring, a rod 301 carrying the spring and pivoted at 302 to the rocking cam member having sliding engagement through a sleeve 303 pivotally mounted in the side frame 82.

Nuts 304 and 305 on the outer end of the rod 301 limit the movement of the rocker member upon each side of its dead center under the influence of the spring.

The rocker member is rigid with respect to its pivot pin 299 which extends through to the inside of the frame 82 and carries at its inner end a lever 306. The outer end of this lever is pivotally connected to the link 307 which in turn is pivotally connected to the rocker arm 285 upon the shaft 288.

As the turret rotates one of the box forms moves into position at which the slot 286 would normally register with the toe 81 of the rocker arm 285.

If there be no box present the form clears the toe by means of the presence of the slot and in this event the cam 298 on the rocker 299 maintains its position in the path of the rack member 294, and when the gripper upon

the registry roll comes to its position of dwell the cam 298 engages and pushes in the rack member 294 and releases the clutch connection between the gears 94 and 102 by withdrawing the pin inwardly against the action of the spring 290.

If, however, a box be present on the form the bottom of the box engages the toe 81 of the rocker arm 285, rocking the arm to move the cam 298 out of path of the rack member 294, the spring 300 maintaining it in rocked position at which it will not engage the rack member to open the clutch.

The spring 300 snaps the cam member out of the path of the extending end of the rack member and in doing so holds the toe 81 away from the bottom of the box upon the form.

After the form has passed and before the next form comes up the toe is returned to its original position by engagement between a lug or projection 309 upon the hub of the gear 94 with a pin 310 upon the rocking cam member 298.

Turn-in clamps

The turn-in clamps are seen in Figures 12, 13, 15 and 27 and the operating mechanism of the shaft is shown in Figures 2 and 4.

The clamps open as the carriage moves up, the roller 153, (Figure 2), engaging a sloping portion 311 of the cam slot 154 to release the side turn-ins from the box and the roller 146 (Figure 4) engaging a sloping portion 312 of the cam slot 147 to release the front and rear turn-ins from the last completed box.

The upward movement of the released box is arrested by its engagement with the bottom of the next box causing the box to stand still and be relatively pushed down through the space between the pressure block clamp members of the upwardly moving carriage. The box finally drops to the delivery belt.

The shaft 159 (Figure 2) operates the side turn-in clamps, as already explained.

The turn-in clamps are substantially all the same except that the eccentric arms 313 operating the front and rear turn-ins (Figure 6) are longer than the corresponding arms 314 operating the side-ins (Figure 15) and that the pressure block of the rear turn-ins is modified to permit the use of blocks of different lengths.

Referring to the diagrammatic Figure 27 of the side turn-ins, the shaft 159 carries an eccentric 315 having a strap 316 with an arm 317 bored to receive a rod 318 having an eye 319 at its outer end and a head 320 screwed on its inner end.

The rod carries a heavy spring 321 which is pressed between the head 320 and a bushing 322 screwed into the end of the arm.

The eccentric rocks bell crank 323, which is pivoted at 324 to the back of one of the side carriers as 176 (Figures 12 and 15) and has fork connection 325 to the eye 319 of the rod 318.

An operating arm 326 which is desirably a piece of cold rolled steel pinned into the end of an L casting bell crank has loose sliding connection at its outer end in a slot 327 through a transverse pin 328 pivotally mounted through the upper end of a vertical rack member 329.

This rack member slides vertically within housing 330 upon the back of the carrier and the housing carries a pinion 331 meshing in the rack. Reduced portions 331' of the pinion member are supported in any suitable bearings 332, and alined crank pins 333 from opposite ends of the pinion member are provided with flange connections 333' with the journal portions 331' and have pivot connection with the inner end of the clamp member 335. The housing extends laterally at 336 to form the pressure block clamp 337 which supports the heavy pull (outward from inside the box) of the turn-in member 335. The spring 321 makes this pull resilient.

The lateral extension 336 pivotally supports a downwardly extending link 338 which at its lower end has pivotal connection at 339 with the clamp member 335.

The clamp member 335 extends outwardly and carries at its outer end a downwardly directed hook 340 inside of which is fastened a removable angle 341 cut to fit the box interior and held to place by any suitable plate 342 and screws 343.

In Figure 13 the clamp is shown in closed position, the wrap having been turned in over the top of the box and clamped back against the box at 344.

As the rack member 329 is moved upwardly by the bell crank by means of the eccentric 315 the hook member moves inwardly and then upwardly releasing the top of the box, this release taking place while the carriage is moving upwardly by reason of engagement between the roller 153 and the sloping portion 311 of the cam 154.

When the carriage begins to move downwardly after sweeping up the wraps upon the sides of the box the box strippers 75 have already moved down to reach the bottom 50 of the box and follow down resiliently pushing the box from its form, the strippers then moving up out of the way and the turret starting toward its next position, the carriage continuing to move downwardly with the box 55 supported upon the supporting rods 77 which had moved into position to receive the box before the box was pushed off from its form.

When the roller 153 fitting in the cam slot 154 again reaches the sloping portion 311 of the cam the turn-in clamps begin to turn in, the angle 341 describing a curved path somewhat like the dotted line 345 of Figure 27, pushing the wrap inwardly over the top of the box and clamping it back against the box 65 which supports the heavy resilient pull of

the turn-ins by the pressure block 337 which fits against the outside of the box.

The long-side turn-in clamps operate just before the end turn-in clamps to properly fold the corners and to avoid striking together of the two pairs.

The resilience of the clamping pull is due to the compression of the heavy spring 321 between the head of the bolt of the rod 318 and the bushing 322 of the eccentric member 75 315.

The short-side turn-in eccentric 315 mounted on shaft 159 has a movement greater than that required for the turn-in operation in order to operate the support rods 77.

The greater movement occurs while the turn-in is out of the box and rotates face cam 346 to move about the shaft 159 the sleeve 347 carrying the support rods 77 to position under the box.

On the upward motion of the carriage the support rods 77 move out of the way as the turn-in clamps are releasing and move back to place under the next box when the wrapping mechanism reaches its highest position. The support rods 77 are or may be in place beneath the box throughout much of the upward motion of the wrapping mechanism and throughout the downward motion of the wrapping mechanism.

Rear turn-in clamp

The rear turn-in clamp is adjustable in length to fit boxes of different length. The pressure foot on each of the other turn-ins 100 is made sufficiently long for a box of maximum length, the excess length of the presser foot doing no hurt. In the rear turn-in, however, the presser foot fits between the opposing presser feet of the side turn-ins so that 105 the structure has to be adapted to easy control of the length of the presser foot, and in practice the rear presser conveniently comprises an angle cut to suitable length and removably fastened to supporting structure 336 110 (Figure 27).

Support rods

The support rods 77 and turn-in clamps for the short sides are both operated by the shaft 115 159, the operation of the support rods being by means of a rotary face cam 346 (Figure 14) cooperating with a face cam 345 upon a sleeve 347 on the shaft 159. The cam member 346 is housed by the side carrier and is splined 120 to the shaft 159 so as to turn with the shaft and also slide along the shaft with the side carrier 175 or 176.

The cooperating sleeve member 347 carries one of the support rods 77, slides on shaft 125 159 and is spring-pressed toward engagement with the member 346 by a spring 348 surrounding a bolt 349 carried by the side carrier and extending through a counterbored hole 350 in the member 347. The spring en- 130

gages the head 351 of the bolt and the bottom of the counterbore 352 in the sleeve member and presses the cam members together.

This member 347 carrying one of the support rods slides freely on the shaft 159 but is kept from angular movement around the shaft, preferably as shown in Figure 14. There the front tie-rod 160 is plowed at 353 to receive a tongue 354 rearwardly projecting from the carrying member 347, which effectively prevents angular movement.

The carrying member supports a vertical rod 355 which in turn carries the transverse support rod 77, which is vertically adjustable 15 at 356 as shown in Figure 1.

The additional turning movement given to the shaft 159 to effect the operation of the support rods is received from the cam 124 (Figure 2) upon the main driving shaft 84.

20 This cam operates through the horizontal link 125 to oscillate the pinion 128 that is upon one of three short equal-arm and parallel eccentrics 128' that pivotally carry the cam member 155 which cooperates with the 25 bell crank 152 to oscillate the shaft 159 of the side turn-ins and support rods.

The slotted cam member 155, carried by the parallel short arm eccentrics 128' (Figures 2 and 2^a) is laterally oscillated by the reciprocation of the horizontal rack member 125, to give the necessary additional movement to the shaft 159 of the side turn-ins, sufficiently to operate the support rods, the additional movements taking place at near dead 35 center of the turn-in eccentrics and taking place at a time when the carriage is in its uppermost position.

The three parallel eccentric members 128' have each a pin portion 128² in the slotted cam, a body portion 128³ having stationary journal support 128⁴ in the side frame 83 of the machine, a flange connection 128⁵ between the pin and body portions and a removable retaining head 128⁶ on the outside of the 45 frame.

Of the retaining heads two, on the upper members, are merely collars and one, on the lower member, is the pinion 28 adapted to be oscillated by longitudinal movement of the 50 rack 125.

The parallel arms of the eccentric members are sufficiently near to the vertical so that angular movement of the pinion head gives the desired lateral arcuate movement 55 of the slotted cam member.

The mounting of the side turn-ins and support rods upon the same shaft 159 is advantageous in simplifying and lessening the requisite mechanism.

60 *Housing of turn-ins*

In practice the inside clamp members 341 are removable angles cut to the inside lengths of the boxes that are being worked upon and 65 these angles have to be replaced by others

of different length to correspond with the inside lengths of other boxes.

The outer clamping members (the pressure blocks) except at rear are of indefinite length greater than the length of the respective box sides so that the pressure block of the rear turn-in is the only one that need be of definite variant lengths.

70 In practice it is usually desirable to remove the respective clamping mechanisms of the turn-ins when changing the clamp elements to fit a box of given dimensions and I show in Figures 12 to 15 a structure that is well adapted to this.

75 The figures represent the side turn-ins carried on the side carriers 175 and 176 respectively, and each of which also supports a side brush and, a side roll and houses the front and rear corner-lap discs.

80 The main casting 357 of the carrier has a portion 358 that forms the upper end of the housing 330 for the vertical rack member 329 operating the side turn-in.

85 The lower portion 359 of the housing 330 is made to unlatch and lift away with the 90 clamping mechanism.

95 In the structure, best seen in Figure 13, the vertical rack member 329 comprises a vertical rod 360 carrying the slotted pin bearing 328 for the operating arm 326 and a sleeve 361 having the rack and fitting over a reduced portion 362 of the vertical rod 360.

100 The bottom of the rod 360 is notched at 363 and the sleeve rack member 361 is provided with an enlarged end 364 perforated at the notch. The reduced rod passes through a perforated pin 365 which fits in a perforation 366 in the enlarged end of the sleeve. The perforation in the pin is sufficiently large to pass the catch on the end of 105 the reduced rod.

110 Normally the pin is spring-pressed at 367 to lock in the catch and prevent the removal of the sleeve rack portion.

115 The lower portion of the housing has a flange-fit 358 with the casting 359 of the side carrier to which it is removably fastened in any suitable way, as by means of a horizontally movable latch 369 supported by the bolts 370 and 371 which depend from opposite sides of flange 372 on the bottom of the casting 357, the horizontal latch fitting into a horizontal groove 373 of the lower housing member 359.

120 When it is desired to remove the turn-in clamp the fastening between the upper and lower portion of the housing is loosened and pin 365 (Figure 13) is pushed in against the action of the spring 367 when the whole turn-in clamp with the lower portion 359 of its housing will slide down.

125 A flange 368 is adjustably fastened to the bottom of the housing 359 the opposite sides of which are provided with holes to match 130

the reduced portion 373 of the supporting bolts 370 and 371 to accurately line up the turn-in with the side of the box.

Corner-lap discs

5 The corner-lap discs 72 (Figures 1, 7, 16, 23 and 26) have splined mounting on the shafts 142 and 139 which are respectively mounted in the front and rear carriers and have housing connections with the side carriers. The front carrier is stationary and does not move. The rear carrier 166 is adjustable forwardly and rearwardly, carrying with it the splined shaft 139 of the corner-lap discs. 10 15 The corner-lap discs are adjustable laterally by the respective side carriers which have resilient connection with the housings of the corner-lap discs.

The housings 374 of the corner-lap discs are 20 maintained against angular movement on the disc shaft by a horizontal tongue 375 (Figures 23 and 26) which is part of the housing and which slides in a groove 376 along the rear carrier.

25 The disc housing has also a downwardly extending lug 377 (Figure 26) which carries an adjustable horizontal bolt 378 which slides in a hole 379 through an upwardly projecting lug 380 of the side carrier.

30 For the rearward corner-lap discs this lug is part of a sleeve 381 slidable along the shaft 181, which latter is used to laterally adjust the carrier, while for the forward discs the lug has no movement forward and rearward, being rigid with respect to the carrier.

A compressed spring 382 (Figure 13) surrounding the bolt 378 presses apart the lug members 377 and 380 of the disc housing and the side carrier, respectively. The forward 40 position of the disc with respect to the carrier being limited by engagement between the head 383 of the bolt with the lug 380 of the carrier.

The corner-lap discs are very valuable features of my invention and admitlapping over 45 the ends of the box with continuous rotary motion instead of motion of translation.

After the long sides of a box have been smoothed up first by the brushes and then by the rolls, the corner-lap discs lap over and smooth up the corner-laps over the ends, with a continuous rotary motion.

50 A corner-lap disc is shown by itself in Figure 16. It is beveled away at 384 and notched at 385 in the middle of the bevel.

The bottom of the box is always in the same plane for all boxes and the corner-lap discs are so timed that when they engage the corners of the wraps the notches 385 register 60 with the bottoms of the sides of the wraps so that the wraps enter the notches.

The bevel portion engages the side of the box and as a result the box pushes the disc back somewhat against the spring 382 increasing the pressure of the disc upon the side

of the box. The disc turns in a direction to pull the wrap inwardly away from the corner so that after the rotating disc has progressed across the ends of the box the corner-laps have been properly turned. 70

Brushes

The front brush 70, (Figures 1, 6, 7, 12 and 24), is mounted upon the stationary front carrier upon preferably front and rearwardly adjustable brackets 386, and 387. The bristles are progressively higher toward the middle of the brush than toward either side, the bristles engaging the middle of the box first and progressively later toward each side. 75 80

The rear brush is like the front brush with the same symmetrical arrangement of high bristles in the middle and progressively lower bristles toward each side, and is mounted upon the rear carrier upon brackets 388 and 389 which are similar to the brackets supporting the front brush, and preferably forwardly and rearwardly adjustable for wear.

85 The side brushes 73 (Figures 1, 7, 12 and 13) are mounted upon the side carriers and a special arrangement is provided for automatically maintaining the high part of the brush at the middle of the box irrespective of the width of the box, the adjustment being such that the middle of the brushes on the side carriers always maintain a position mid-way between the front and rear brushes. 90 95

The mechanism for automatically maintaining the middle of the side brushes always half way between the front and rear brushes 100 is a valuable feature of my invention and is best seen in Figures 12, 13 and 26.

The brush 73 is mounted in laterally adjustable bearings 390 and 391 upon a sliding sleeve or carriage 392. The carriage 392 is carried upon the sleeve 381 which slides on the shaft 181 and which is positioned along the shaft 181 by connection at the bolt 378 with the housing 374 of the corner-lap disc, as already explained. 105 110

The sleeve 381 slides forwardly and rearwardly with forward and rearward movement of the rear carrier and the corner-lap disc housing slides laterally with lateral motion of the side carrier.

115 The sleeve 381 carries a pinion 393 pivoted to the sleeve 392 at 394 and rolling at the bottom in a rack 395 that is rigidly fastened to the side carrier and rolls at its top in a rack 396 cut upon the bottom of the sleeve 381. 120

The sleeve 381 moves forwardly and rearwardly with the rear carrier, rolling the pinion 393 between the racks 396 and 395, the bodily movement of the pinion being one-half that of the sleeve 381. 125

The brush carriage 392 is positioned by the pinion 393 which it carries and therefore moves with just half the motion of the sleeve 381 or half of the forward or rearward adjustment of the rear carrier. 130

The front carrier has no adjustment and is always in the same position irrespective of box size. When the box size is changed the rear carrier takes all the adjustment and to maintain the brush central with respect to the sides between the front and rear carriers its supporting carriage 392 is thus geared to move one-half as far as the movement of the rear carrier.

10 *The rolls*

There is one roll on each carrier and all of the rolls are supported to turn freely in bearings and to make resilient engagement 15 with the side of a box upon which they are rolling.

The front and rear rolls are supported by brackets 397 (Fig. 12) on the front and rear carriers. The bearings into which the rolls 20 journal at these brackets are resiliently pressed outward in any suitable way not shown.

The side rolls have no forward and rearward adjustment with forward or rearward 25 movement of the rear carrier but the resilient pressure upon the side roll is automatically maintained central with respect to a box that is half way between the front and rear carriers.

30 The roll is journaled in a carrying member 398 (Figures 12, 13 and 26) which is supported at its ends upon suitable horizontal pins 399 that extend slidably into supporting brackets 400 near opposite ends of the side 35 carrier.

The carrying member 398 extends across the brush carriage 392 and spring-pressed 40 shoes 401 and 402, one upon each side of the pinion 393 upon the carriage 392 resiliently press the back of the carrying member outwardly. The outward motion is limited in any suitable way as by screw adjustment at the pins 399.

45 The engaging surfaces of the brush, roll and corner-lap discs of the same carrier are preferably substantially vertically in line but when a box is not present are all somewhat in beyond the position for the outside surface of the box, there being a slight allowance for resilience of engagement.

50 With the brush this resilience is in the bristles. With the rolls of the front and rear carriers it is due to springs at the roll bearings, and with the side rolls is due to 55 springs carried by the brush carriage 392 one on each side of the pinion 393.

With the corner-lap discs this resilience is due to the spring-support 382 as already described.

60 The carriage 89 is counterweighted by means of springs 403 and 404 (Figures 2, 6 and 7).

A rod 405 is pivoted at 406 to each of the 65 rocker arms 113 and 114 on the rocker shaft 88, and extends downwardly through a per-

forated pin 407 that is pivotally carried in the frame structure, one on each side. The counterweighting springs are carried one upon each of the rods 405, compressed against the supporting pins 407 so as to upwardly 70 press the rods to take the weight of the carriage.

At the low position of the carriage the rocker arms 113 and 114 make an obtuse angle with the rods and as the carriage is raised 75 this angle becomes more nearly a right-angle increasing the length of arm of the lifting moment as the strength of the spring diminishes due to its extension and thus effects an approximate uniformity in the counterbalancing effect of the springs.

Strippers (Figures 2, 4, 6, 7 and 8)

The box strippers 75 are operated by means of the cam 117 mounted upon the main driving shaft 84. This cam engages the roller 120 of the bell crank 118 which is pivoted at 408, spring-pressed at 119 to cam and roller engagement, and carries a link 121 which operates the shaft 123 having toothed end 90 sectors 122 and 410. The sectors 122 and 410 mesh with gears 411 and 412 respectively mounted upon shaft 413 and 414 which extend inwardly, (see Figure 8), through laterally adjustable housings 415 and 416 carried 95 by square bars 417 and 418 respectively from the sides.

The shafts 413 and 414 have splined connection with pinions 419 and 420 in the housings 415 and 416 that respectively mesh with 100 rack members 421 and 422 one on each side of the body of the turret.

Each rack member extends downwardly to form one of the front strippers 75, the rearward stripper 75 depending from a horizontal rod 425 that is rigidly fastened to the rack member in any suitable way.

Each rearward stripper is adjustable at 426 along its horizontal supporting rod 425 and each rack member is adjustable in its 110 spacing from the body of the turret so that the strippers are readily adjusted to any size of box form.

The length of the strippers has to be somewhat more than twice the maximum depth 115 of a box in order to be able to clear the form, as the stripper must entirely clear the box from the form by passing down through the form while pressing on the bottom of the box.

The stripper shaft 123 passes through the 120 hollow shaft 85 carrying the turret.

The stripper rods start to move down when the turret reaches its third position, and moving downwardly through the form reach the bottom of the box when the carriage is in 125 its highest position, following the carriage downward far enough to strip the box from the form.

The strippers and the supporting rods move down together, the strippers resiliently 130

pressing the bottom of the box against the support by the action of the spring 119 at the rocker arm 48 and the cam 117 effects the rapid return of the strippers after it has moved down far enough to strip a box of maximum depth from the form.

Adjustable crank

The crank 105 on the left-hand end of the main drive shaft 84 connected to move the carriage up and down, is provided with an offsetting adjustment of throw, at 427, the crank pin 428 being adjustably positioned along an offsetting guide 429 by means of a screw 430, as shown in Figure 2.

The need for this adjustment is to adapt the mechanism to operate on boxes of different depths.

The bottoms of boxes on the turret forms 20 are always in the same plane when the boxes are operated upon by the brushes, rolls and corner-lap discs, and the notch of each corner-lap disc meshes with bottom corners of wraps always in this one plane, so that one 25 setting of the corner-lap discs is right for all depths of boxes.

The operation of the turn-ins is upon the top of the box and during the down stroke of the carriage, always taking place at substantially the same carriage height whatever 30 the depth of the box, the cam operating the turn-ins being fastened to the side of the frame.

As the bottoms of the boxes are always in 35 substantially the same plane, the tops of the boxes will vary with different depth boxes. At the highest point of the carriage travel it is necessary that the tops of the boxes 40 register with the pressure blocks and turn-in clamps, thus the necessity of varying the stroke of the carriage to bring the pressure blocks in the right position.

Furthermore, it is desirable to have the carriage in relatively the same position with 45 respect to the form when the turret is ready to turn, the turret starting to turn toward its next position of dwell during the downward travel of the wrapping mechanism as soon as the box clears the form.

This is accomplished by changing the stroke of crank 105 which regulates the amount of travel of the carriage, and the offset position of the screw 430 governs the timing necessary to have the carriage in position in relation to the form mentioned above.

When the box depth is changed the position of the crank pin 428 is adjusted by means 60 of the screw 430 to accord with the new depth, so determined by any suitable scale 431 along the guide, and the support rods are then vertically adjusted to bring the box in proper relation with the turn-ins, the upper 65 edge of the box having to come about

one-eighth of an inch below the top of the pressure blocks.

The turn-in is usually about half an inch.

Box grippers (Figures 6, 8, 9 and 10)

While in many cases it may be found unnecessary to use any clamping mechanism to hold the boxes to the box form during its travel from the registry roll to position for wrapping up the sides of the box I have illustrated such clamping mechanism in the drawings.

As already explained the box grippers 68 are operated by means of the cam 69 which is rigid with respect to the sleeve 135 and is 70 operated from the main driving shaft 84 by the cam 129 cooperating with the arm 130, the vertical shaft 131, sector 132, and the rack member 133 that meshes with the sleeve 135.

The clamp 68 is carried upon a helical gear 431 which is housed in the washer or sleeve member 207 upon the tubular arm 196 of the turret.

The gear 431 meshes with a corresponding 90 helical gear 432 which is splined upon the shaft 433 and supported in a housing 434 having pin support upon the sleeve member 207 at 435 through the slot 200 in the tubular arm of the turret.

The splined shaft 433 carries a gear 436 at its inner end and this gear meshes with bevel teeth 437 of a guided rack member 438 which is operated through a link 439 and a rocker arm 440 by the cam 69.

The rocker arm carries a roller 441 and is spring-pressed at 442 to maintain roller engagement with the cam which is synchronized in its movement with the operation of the drive shaft as already explained.

Adjustment to different sizes of boxes (Figures 2 and 17)

The position at which the gripper arms 240 and 241 stop in carrying a wrap around the registry roll is varied according to the depth of the box.

Initial engagement between the bottom of a box and the registry roll is always at the same place whatever the box size, being always along the forward corner of the form 58 on the turret while the turret is in dwell.

The width of wrap upon the registry roll beyond this line of initial engagement is equal to the depth of the box plus the small additional amount needed for turn-ins and therefore must vary with and be adjusted to the depth of the box.

The shaft 237 carrying the gripper arms is made angularly adjustable with respect to the gear 229 and therefore with respect to its angular position during the dwell of the driven intermittent gear 225 which drives the gear 229.

This permits setting the arms to stop at 130

any desired position to accord with any depth of box.

Desirably a V-notch-and-pin latch 443 operates when the driven intermittent gear 225 reaches its dwell to exactly position the gear 229 and therefore the gripper arms with which it is rigidly connected.

This latch avoids any variation from the set position by reason of lost motion in the gears. The movable member 444 of the latch is pivoted at 445 to the stud 446 pivoting the driven intermittent gears and is spring-pressed at 447 toward latching engagement between the V-notch 448 of the latch member and a pin 449 carried by the gear 229. The pin 449 registers with the notch at the beginning of the dwell of the driven intermittent gear 225 and the latch is opened before the end of the dwell by engagement of a cam 20 450 on the gear 220 with a toe 451 of the latch member.

Depth-of-box adjustments involve an adjustment of the angular position of the gear 229 upon the shaft 237 to set the stopping 25 positions of the gripper, a corresponding reverse adjustment in the angular position of the gear 220 with respect to its driving shaft 87 to maintain unchanged the position of gripping, an adjustment of the offset crank 30 105 and a vertical adjustment of the support rods. Width-of-box adjustments involve a change of the front and rear turn-ins, and adjustments in the position of the rear carrier and in the lateral position of the box stripers.

Length-of-box adjustments involve changing the side turn-ins, positioning the side carriers and positioning the rear stripper rods.

Structures similar one to the other, that are 40 particularly well adapted for making the adjustments in the angular setting of the gears 229 and 220, are shown in Figure 17 at 223 and 239.

The hub 452 of the gear 229 mounted upon 45 the sleeve 238 has a radial T groove 453 (Figures 17 and 20) in its outer face and an outer flange 454 of the sleeve is bored at 455 to receive a cylindrical clamp member 239. This clamp member has an inner cylindrical portion 456 fitting the bore and carries a bolt 457 having a head 458 sliding in the T groove. The body 459 of the bolt fits a hole 460 through the clamp member, the hole being eccentric 50 with respect to the axis of the cylinder.

The bolt is provided with a nut 461 upon its outer end and the adjoining faces of the outer flange of the inner sleeve 238 and of the gear 229 are bolted together by tightening the 55 nut 461.

When the nut is loosened the cylinder 456 may be turned and by reason of the eccentricity of the axis of the bolt with respect to the axis of the cylinder the bolt, acting like a 60 crank, changes the angle between the sleeve

and the gear at the same time altering its sliding engagement in the T groove.

The clamps 223 and 239 are desirably exactly the same and are provided with knurled handles 462 for setting. Desirably also a dial 463 is provided upon the circumference of each cylinder 464 with a corresponding line of reference upon the face of the sleeve member.

A given setting on the upper dial should 75 correspond to a similar setting of the lower dial, as this makes it very convenient to adjust the setting of boxes of different depth, the setting being merely that of turning the upper and lower knurled handles to the 80 proper dial reading and then tightening the bolts.

Turret register

A disc 465 (Figures 2 and 8) is rigidly 85 keyed to the turret shaft 85 and provided with three V-notches 466 to correspond with the three arms of the turret 86. A pin 467 in the bell crank 468, pivoted at 469 and spring pressed at 470 to engagement with 90 V-notch, accurately positions the turret at its three positions of dwell.

The pin 467 is disengaged from its locking position in the V-notch 466 by means of engagement with a cam 471 rigidly fastened 95 to stripper sector 410 and located in respect to the sector so that the engagement of cam 471 and pin 467 takes place at the extreme upward position of the strippers 75 when the turret is ready to move.

The strippers, starting their downward travel when the turret reaches its position of dwell, cause cam 471 to move away from pin 467 allowing its engagement with V-notch 466, to exactly register the dwell of the turret.

As a matter of convention and because it is more convenient to arrange the cycle in the way in which I have indicated applying the wrap to the box during the downward movement in the upper left sector of travel 110 as shown in the drawing and giving vertical movement to the wrapping mechanism, I have constantly referred to the cycle from these standpoints but there is neither theoretical nor mechanical reason why this arrangement of the cycle must be maintained.

The wrap could be applied initially to the box at another point in the circumference and the wrapping of the sides, operation of turn-in, etc., could correspondingly be performed 115 at a different position in the circumference by motion in a different direction than indicated. This will be obvious from the fact that except as the glue might spill and not apply properly the whole machine would 120 work if turned bodily at any angle. The motion should be perpendicular to the box bottom.

Understanding that the statute requires me to describe the best mode known to me 125

for practicing my invention, I have gone into great detail in describing a full size operative machine commercially practicable to perform the functions and carry out the operations described but of course have no thought of restricting my invention to this form and intend my claims to be read broadly as covering the many other forms and characters of operation coming reasonably within the spirit and scope of my invention. In view of the disclosure herein variations and modifications to meet individual whim or particular need will undoubtedly occur to others skilled in the art and I shall of course desire to be protected against such appropriation by them of my invention.

Having thus described my invention what I claim as new and desire to secure by Letters Patent is:

20. 1. In the art of wrapping the bottom, sides and ends of a wrap upon the outside of a box, the method which consists in registering the box with the wrap supply by the forward edge of the bottom of the movable box independently of the length of the box, in applying the wrap initially to the forward edge of the bottom of the box as thus registered and in applying the remainder of the bottom of the wrap to the bottom of the box by movement of the box.

25. 2. The method of applying a wrap to a box which consists in resiliently pressing a glued wrap into engagement with the bottom of a box, and in applying the wrap to the bottom of the box by movement of the box.

30. 3. The method of applying a wrap to the bottom of a box which consists in pressing the glued wrap to register against a forward edge of the bottom of the box while the box is stationary and in rotating the box bodily about an axis distant from the box while maintaining the wrap-applying pressure in its initial plane of pressure application.

35. 4. In the applying of wraps to the outer bottoms, ends and sides of boxes, the method which consists in moving the box with the bottom outward, in stopping the box, in applying the wrap to the forward edge of the bottom of the box, in moving the box forwardly while coincidentally applying the bottom of the wrap to the bottom of the box, in again stopping the box and in holding the box in a stopped position while applying the sides and ends of the wrap to the sides and ends of the box.

40. 5. The method of wrapping boxes of different sizes which consists in registering all the bottoms and forward ends of the boxes to definite planes of initial position, irrespective of the sizes of the box, and in registering the wraps initially to make engagement with the edge of the box in the same position of successive boxes.

45. 6. The method of wrapping boxes of different lengths, which consists in registering

the bottoms and forward ends of the boxes initially in the same definite positions irrespective of differences in size of the boxes, in registering the wraps for application to the boxes with respect to the same position of the fronts of all of the boxes and applying them to the boxes in this position and in side wrapping the boxes in another box position in which the fronts of all of the boxes side wrap in the same plane.

70

7. The method of wrapping boxes, which consists in placing the boxes successively in position with their front ends in the same plane, in bringing the wrap into engagement with the front end of the box while the box is stationary and in rolling the wrap upon the box bottom by revolution of the box.

75

8. The method of turning in the corner-laps of a box wrap upon the sides of a box which consists in progressively turning in the corner-laps in curved lines by rotarial progressive pressing action.

80

9. The method of turning in the corner-laps, which consists in rotarially pressing the corner-lap progressively along the length of the corner lap.

85

10. In using box-wrapping mechanism and a box form carrying a box to side wrap a wrap already on the bottom of the box, the method which consists in sequentially brushing and rolling opposite sides, rotarially corner-lapping, and brushing and rolling the ends with a single sweep of the wrapping mechanism.

90

11. An intermittently movable turret, radially outwardly directed box forms thereon, mechanism for applying a wrap to the outwardly directed bottom of a box on one of the forms, and other mechanism operative subsequent to the first during a dwell of the turret for applying the sides and ends of the wrap to the sides and ends of the box while the box is still on the form and by a movement substantially radial to the axis of the turret.

100

12. In an automatic box wrapping machine, a turret having successive periods of movement and dwell, box forms adapted to carry boxes on the turret at the same radial distance from the axis of the turret, a registry roll for applying wraps to the successive boxes on the forms and mechanism for wrapping the ends and sides of the successive boxes while they are on the forms, in combination with mechanism for registering the applications of the registry roll and the applications of the wrapping mechanisms both with respect to different dwell positions of the forward ends of the box forms.

105

13. In a box wrapping machine, an intermittent turret or carrying alternatively variant sizes of box forms, each box form being adapted to receive a box of size corresponding to the form size, and fastening mechanisms on the turret adapted to fasten

110

115

120

125

129

- the forms to place so that the bottoms and forward ends of the forms are in definite planes, which planes are the same for the different sizes of forms and that successively 5 dwell in the same positions, in combination with wrap-applying mechanism operative while the boxes are upon the forms and the forms upon the turret. 14. In a box wrapping machine, an intermittent turret for carrying alternatively variant sizes of box forms, each box form being adapted to receive a box of size corresponding to the form size, and fastening mechanism on the turret adapted to fasten 10 the forms to place so that the bottoms and forward ends of the forms are in definite planes, which planes are the same for the different sizes of forms and that successively 15 dwell in the same positions, in combination with a registry roll adapted to apply successive wraps to the bottoms of successive boxes in registry with the forward edges of the bottoms of the boxes while they are successively in one position of dwell, and other 20 mechanism movable substantially radially to the turret during dwells of the turret in registry with another of the dwell positions of the forward ends of the successive forms, and adapted to apply end and side portions of the 25 wraps to the boxes. 15. In a box wrapping machine, a turret, box forms thereon adapted to receive boxes and to present them with their bottoms radially outwardly from the turret axis at uniformly 30 spaced intervals around the turret, a registry roll adapted to receive glued wraps for application from the roll to the bottoms of the boxes, and mechanism adapted to give the roll rotary movement on its own axis 35 while it is receiving a wrap and to bodily swing the roll into resilient engagements with the bottoms of the boxes during periods of dwell of the turret and to maintain the resilient engagements during the advancing 40 movements of the turret in order to apply the wraps to the bottoms. 16. In a box wrapping machine, a carrier having alternate periods of movement and dwell, a box-form thereon adapted to carry 45 a box and to present it bottom outwardly in a definite position during a period of dwell of the carrier and means for placing a box wrap in registry upon the bottom of the box so that in the position of dwell the bottom of 50 the box carries the wrap, in combination with reciprocating wrapping mechanism alined with the sides and ends of the box in its position of dwell and adapted in a single sweep of the mechanism to sequentially brush and 55 roll opposite sides, corner-lap the projecting end flaps of the side positions of the wrap and brush and roll the ends of the wrap on to the ends of the box. 17. In box-wrapping machinery, an intermittent turret having arms forwardly offset 60 from the turret axis and box forms removably fastened at their forward ends to the respective arms. 18. An intermittent turret, arms forwardly offset from the turret axis on and uniformly spaced around the turret, box forms removably fastened to the arms near one side of the respective forms and rearwardly extending from the fastening, and a registry roll adapted to register wraps with the forward 65 ends of boxes on the forms. 19. An intermittent turret, arms forwardly offset from the turret axis uniformly spaced around the turret, box forms removably fastened to the arms at near their forward 70 sides and having a slot in each forward corner, a wrap-applying roll adapted to apply wraps to the bottoms of boxes on the forms, shut-down mechanism adapted to shut down the roll before the roll engages an adjacent form, and a trip lever before the wrap-applying roll registering with the slots and normally engaging each roll-approaching 75 box to prevent the operation of the shut-down when a box is present. 20. In box-wrapping machinery, an intermittent turret, arms uniformly spaced there-around, a threaded and forwardly slotted tubular extension in each arm, a cross bar pivotally mounted in the outer end of each extension and adapted to turn axially thereof through the slot into the tube, a box form perforated near the middle of its forward side at a definite distance from its forward edge and recessed on its bottom perpendicular to its side at the perforation, and the box form mounted upon the extension through its perforation, the cross bar fitting the recess, and a nut on the extension clamping the 80 form to the cross bar. 21. An intermittent turret having an arm, a cross bar pivotally mounted on the outer end of the arm and adapted to turn axially to pass the perforation of the form, a forwardly perforated box form mounted through its perforation on the arm and recessed in its bottom to receive the cross bar, a washer on the extension engaging the top of the form, a trunnion fastened to the upper side of the washer upon each side of the extension, a sleeve having lugs, surrounding the extension above the washer and adapted to turn on the trunnion, a nut on the extension adapted to clamp the sleeve down against the trunnion, lateral screws threaded downwardly through the lugs on the sleeve to engage the washer and adapted to rock the form upon the trunnion. 22. An automatic box-wrapping machine, an intermittent turret, a hollow shaft supporting it, box forms carried upon the turret, roll mechanism adapted to apply wraps to the bottom of boxes upon the forms, side-wrapping mechanism adapted to wrap the 85 sides of a box while the box is on the turret. 130

- form, a pair of strippers adapted to strip a box from its form after side-wrapping, a shaft inside the hollow shaft for operating the strippers and connections between the inside shaft and the strippers.
23. An intermittent turret having arms and a hollow shaft, a box form on one of the arms presenting a box to side-wrapping mechanism, strippers adapted to strip the box from the form after the operation of the side-wrapping, an operating shaft of the strippers passing through the hollow shaft of the turret and connections between the inside shaft and the strippers.
24. In a box-wrapping machine, a turret adapted to present boxes upon box forms for bottom and side wrapping, a hollow shaft upon which the turret is adapted to operate, mechanism adapted to wrap the bottom and sides of a box carried upon one of the forms, a driving shaft, supporting frame structure journaling the hollow shaft of the turret and the driving shaft, a cam mounted upon the driving shaft, strippers supported upon each side of the turret for stripping a box from its form after side-wrapping and operative resilient connection between the cam and strippers through the hollow shaft of the turret stripping by spring pressure and returning the strippers by positive action of the cam.
25. An intermittent turret having hollow arms, a box form on each arm, each form being adapted to receive a box and to present it with its bottom radially outward from the turret axis, a box gripper adapted to operate to hold the box to its form for a predetermined portion of the travel of the turret, and mechanism passing through the hollow arm for operating the grippers.
26. In a box-wrapping machine, side-wrapping mechanism, an intermittent turret carrying a box form and adapted to present the form in dwell in radial alinement with the side-wrapping mechanism and a box gripper operative to hold a box to the form as it approaches the dwell and to move out of the way of the advancing side-wrapping mechanism.
27. In a box wrapping machine, upwardly directed and vertically reciprocating side wrapping mechanism, an intermittent turret rotating in a vertical plane about a horizontal axis, a box form carried on the turret and adapted to receive a box and to be presented during a period of dwell of the turret vertically downward above the side wrapping mechanism, and a box gripper operative to hold a box to the form as it approaches the dwell and to move out of the way of the upwardly moving side wrapping mechanism operative during the dwell.
28. In mechanism for corner-lapping a projecting corner-lap of a wrap upon the end of a box, means for holding a box, a disc, other means making the disc simultaneously revolve on its own axis and make overlapping resilient engagement with the edge of the box while moving along the edge of the box adapted to simultaneously over-lap one edge of a box, resiliently laterally engage it and move along it.
29. A corner-lap disc having a recess and adapted to over-lapping travel along an edge of a box, means for driving the disc synchronized to mesh the recess with the bottom of a lap and adapted to carry the revolving disc overlapping the edge of a box progressively along the lap.
30. A corner-lap disc having a recess and beveled away at the recess, a housing of the disc resiliently pressed inwardly beyond the outer surface of a box, and driving mechanism for the disc meshing the recess with the bottom of the lap and engaging the box in the bevel portion of the disc and progressively moving the rotating over-lapping disc along the box while the disc is pushed back somewhat by reason of the engagement of the bevel with the box.
31. In an automatic box-wrapping device, a wrap-applying roll, wrap-gluing mechanism, arms having common axis with the roll, a wrap gripper carried between the arms adapted to grip a wrap in synchronism with its presentation from the gluing mechanism and to travel around the roll to present the wrap glue side out upon the surface of the roll.
32. In an automatic box-wrapping device, a wrap-applying roll, wrap-gluing mechanism, arms having a common axis with the roll, a wrap gripper carried between the arms, and jaws on the gripper parallel to the roll and turned to receive a wrap from the gluing mechanism and while traveling around the roll turning inward to bring the wrap to the surface of the roll.
33. In an automatic box-wrapping mechanism, a wrap-applying roll, spaced arms between and on which the wrap-applying roll is mounted, a shaft about which the arms carrying the wrap-applying roll are adapted to swing, a glue-applying roll, a turret carrying a box form, and mechanism synchronized with the turret swinging the wrap-applying roll sequentially into position to receive a wrap from the glue-applying roll, into position to deliver the wrap to the form and back to its first position.
34. A glue-applying roll adapted to deliver glued wraps, a turret synchronized with the wrap delivery and adapted to carry boxes, a registry or wrap-applying roll and mechanism synchronized with the turret and wrap delivery from the glue roll adapted to move the registry roll sequentially into position to receive a wrap from the glue-applying roll, into position to apply it to a box on the turret and then to return the roll to its original position for another wrap.

35. A glue-applying roll, a turret carrying a box for wrapping, a wrap-applying roll having a supporting shaft upon which it is adapted to turn, a gripper, supporting arms therefor fastened to the shaft, a driving shaft 5 parallel to the first shaft, mechanism mounted thereon operating the gripper, arms pivotally carried on the driving shaft and pivotally supporting the shaft of the wrap applying 10 roll, and mechanism synchronized with the turret and glue roll positioning the pivoted arms.

36. A registry roll, a gripper adapted to travel around the roll, a driving shaft, an 15 arm and gear casing rigidly connected together and pivotally mounted on the driving shaft and supporting at their upper ends the registry roll, mechanism synchronized with the turret for angularly positioning the arm 20 and gear casing, and gearing within the casing connected to the gripper adapting the gripper to sequentially grip a wrap, travel around the roll with the roll to a definite stop, to release gripping, to again move forward 25 and to present open jaws for gripping another wrap as it again reaches its original position.

37. A turret, a glue-applying roll, a glue machine having a main cylinder and a shaft 30 therefor, a cam on the shaft, a rocker member adapted to be positioned by the cam, a spring pressing the rocker to cam engagement and 35 cooperating with the cam to position the rocker and a wrap-applying roll between the glue-applying roll and the turret, mounted on the rocker, and adapted to be positioned by the cam synchronously with the operation of the turret and glue-applying roll to receive a wrap from the glue-applying roll and 40 to swing over and deliver it to a box on the turret.

38. A spindle, a wrap-applying roll axially supported thereby and adapted to turn there- 45 with, gripper arms keyed to the spindle at opposite ends of the roll, a wrap-gripper journaled in the outer ends of the arms, a pair of spaced standards rigidly connected together journaling the spindle on opposite sides of the roll, a sleeve adapted to turn on 50 the spindle, a cam rigidly mounted on the sleeve, gripper arm mechanism cooperating with the cam to operate the gripper upon relatively turning the sleeve and arm, a driving shaft, intermittent gearing between the driving shaft and sleeve and other intermittent 55 gearing between the driving shaft and spindle.

39. A spindle, a wrap-applying roll axially supported thereby, a clutch connection be- 60 tween the spindle and roll adapting the spindle to drive the roll, gripper arms keyed to the spindle at opposite ends of the roll, a wrap gripper journaled in the outer ends of the arms, a pair of spaced standards rigid- 65 ly connected together journaling the spindle

on opposite sides of the roll, a sleeve adapted to turn on the spindle, a cam rigidly mounted on the sleeve, gripper arm mechanism cooper- 70 operating with the cam to operate the gripper upon relatively turning the sleeve and arm, a driving shaft, intermittent gearing be- 75 tween the driving shaft and sleeve, other in- termittent gearing between the driving shaft and spindle, and timed mechanism adapted to open the clutch after the other intermittent gearing reaches its dwell.

40. A spindle, a wrap-applying roll on the spindle adapted to turn therewith, gripper arms keyed to the spindle at opposite ends of the roll, a wrap-gripper journaled in the 80 ends of the arms, a pair of spaced standards rigidly connected together journaling the spindle on opposite sides of the roll, a sleeve adapted to turn on the spindle, a cam rigidly mounted on the sleeve near one of the arms, gripper-arm mechanism cooperating with the cam to operate the gripper upon relative turning the arm and sleeve, a drag rod jour- 85 naled between the standards, fingers thereon adapted to engage the roll, a drag finger cam rigidly mounted on the sleeve, resilient oper- 90 ating connection between the second cam and the drag rod carried on one of the standards, a driving shaft, intermittent gearing between the driving shaft and sleeve and other inter- 95 mittent gearing between the driving shaft and spindle.

41. A spindle, a wrap-applying roll sup- 100 ported thereby and adapted to turn there- with, gripper arms keyed to the spindle at opposite ends of the roll, a wrap gripper jour- 105 naled in the outer ends of the arms, a pair of spaced standards rigidly connected to- 110 gether journaling the spindle on opposite sides of the roll, a sleeve adapted to turn on the spindle, a cam rigidly mounted on the sleeve, gripper arm mechanism cooper- 115 operating with the cam to operate the gripper upon relatively turning the sleeve and arm, a driv- 120 ing shaft, intermittent gearing between the driv- 125 ing shaft and sleeve, other intermittent gear- 130 ing between the driving shaft and spindle, an adjustment between the spindle and the first intermittent gearing and a reverse adjustment between the first intermittent gearing and the shaft.

42. A spindle, a wrap-applying roll sup- 120 ported thereby and adapted to turn there- with, gripper arms keyed to the spindle at opposite ends of the roll, a wrap gripper journaled in the outer ends of the arms, a pair of spaced standards rigidly connected together journaling the spindle on opposite sides of the roll, a sleeve adapted to turn on the spindle, a cam rigidly mounted on the sleeve, gripper-arm mechanism cooper- 125 operating with the cam to operate the gripper upon relatively turning the sleeve and arm, a driv- 130 ing shaft, intermittent gearing between the driv- 135 ing shaft and the sleeve, other intermit-

tent gearing between the driving shaft and spindle, an adjustment between the spindle and the first intermittent gearing, a reverse adjustment between the first intermittent gearing and the shaft and reverse scales upon the adjustments marking settings for different depths of box.

43. A spindle, a wrap-applying roll supported thereby and adapted to turn therewith, gripper arms keyed to the spindle at opposite ends of the roll, a wrap gripper journaled in the outer ends of the arms, a pair of spaced supports rigidly connected journaling the spindle on opposite sides of the roll, a sleeve adapted to turn on the spindle, a cam rigidly mounted on the sleeve, gripper arm mechanism cooperating with the cam to operate the gripper upon relatively turning the sleeve and arms, a driving shaft, intermittent gearing between the driving shaft and sleeve, other intermittent gearing between the driving shaft and spindle, an adjustment between the spindle and first intermittent gearing, and a reverse adjustment between the first intermittent gearing and the shaft, each adjustment structure comprising a sleeve radially carried on the end of the shaft or spindle, a gear having a radial T groove on its outer face fitting on the sleeve and adapted to turn thereon, an eccentrically bored radial flange on the outer end of the sleeve fitting against the grooved face of the gear, an eccentrically perforated cylinder fitting the inside of the bore and enlarged outside the bore to engage the face of the flange, and a bolt having a head fitting the T groove, a body fitting the perforation through the cylinder down against the flange.

44. A spindle, a wrap-applying roll axially supported thereby and adapted to turn therewith, gripper arms keyed to the spindle at opposite ends of the roll, a gripper journaled in the outer ends of the arms, a pair of spaced standards rigidly connected together journaling the spindle on opposite sides of the roll, a sleeve adapted to turn on the spindle, a cam rigidly mounted on the sleeve, gripper arm mechanism cooperating with the cam to operate the gripper upon relatively turning the sleeve and arm, a driving shaft, intermittent gearing between the driving shaft and sleeve, other intermittent gearing between the driving shaft and spindle, a latch member pivotally mounted at the axis of the driven intermittent gear of the first intermittent gearing having a V-notch catch in one end, a pin turned with the spindle, spaced from the axis thereof and adapted to register with the notch when the driven intermittent gear reaches its dwell, resilient means pressing the latch toward the pin, and cam means turning with the driving shaft for opening the latch before the end of the dwell.

45. A spindle, a wrap-applying roll axially supported thereby, gripper arms keyed to

the spindle at opposite ends of the roll, a wrap gripper journaled in the outer ends of the arms, a rocker, stationary side supports journaling the rocker, a pair of spaced standards rigidly connected to the rocker journaling the spindle on opposite sides of the roll, a sleeve adapted to turn on the spindle, a cam rigidly mounted on the sleeve, gripper arm mechanism cooperating with the cam to operate the gripper upon relatively turning the sleeve and arm, a driving shaft, intermittent gearing between the driving shaft and sleeve, other intermittent gearing between the driving shaft and spindle, a wrap feed upon one side of the roll, a clutch between the roll and spindle spring-pressed toward opening, a cam carried by the side support adapted to maintain the clutch while the roll is in position near feed, and timed mechanism adapted to swing the rocker to bring the roll into engagement with the box on the turret and to release the clutch.

46. A spindle, a wrap-applying roll axially supported thereby and adapted to turn therewith, gripper arms keyed to the spindle at opposite ends of the roll, a wrap-gripper journaled in the outer ends of the arms and comprising inner and outer jaw members, a pair of spaced standards rigidly connected together journaling the spindle on opposite sides of the roll, a sleeve adapted to turn on the spindle, a cam rigidly mounted on the sleeve, a second cam at the other end of the gripper rigidly mounted on one of the standards, gripper arm mechanism cooperating with the second cam to operate the inner jaw of the gripper upon rotating the arms, other gripper arm mechanism cooperating with the first cam to operate the outer jaw of the gripper upon relatively turning the sleeve and arms, a driving shaft, intermittent gearing between the driving shaft and the sleeve and other intermittent gearing between the driving shaft and the spindle.

47. In automatic wrapping mechanism, a carriage for side wrapping mechanism, comprising end plates, front and rear tie rods therebetween upon opposite sides thereof, a front carrier rigidly connected between the ends, side carriers supported upon and adjustable along the tie rods, and a rear carrier having screw support and forward and rearward screw adjustment.

48. In automatic wrapping mechanism, a carriage for side wrapping mechanism comprising end plates, front and rear tie rods therebetween on opposite sides thereof, a front carrier rigidly fastened between the ends, side carriers supported upon and adjustably along the tie rods, a rear carrier having forward and rearward screw adjustment, and side wrapping and turning mechanism alined on each carrier.

49. In automatic wrapping mechanism a carriage comprising opposite ends having

- rearward journal projections, tie rod rack members rigidly fastening the ends together at opposite sides thereof, a front carrier rigidly fastened between the ends near the 5 front tie rod, a screw near each end of the carriage journaled in the front carrier and in the journal projections of the adjacent end plates, a rearward cross shaft geared to both of the screws and journaled in the end plates, 10 a rear carrier mounted upon the screws, forwardly and rearwardly adjustable thereby, a side carrier housed upon the tie rods, and shaft journaled in opposite ends of the carrier having upon each end a pinion meshing 15 in the rack of the tie rod for lateral adjustment of the carrier.
50. In automatic wrapping mechanism, a carriage for side wrapping mechanism comprising end plates, front and rear tie rods 20 therebetween on opposite sides thereof, a front carrier rigidly fastened between the ends, side carriers supported upon and adjustable along the tie rods, a rear carrier having forward and rearward screw adjustment, 25 means for reciprocating the carriage, a box form adapted to carry a box in the path of reciprocation, a brush and roll upon each carrier adapted to sweep a wrap to the sides of the box, corner-lap mechanism upon the 30 front and rear carriers forlapping the corners, and laterally positioning connection between the corner-lap discs and the side carrier.
51. A carriage, supporting structure with- 35 in which the carriage is adapted to move up and down, a vertical rack on the structure, a pinion meshing in the rack, a driving shaft carrying the pinion and journaling in the carriage, a front carrier rigidly fastened to the 40 carriage, a rear carrier adapted to rearward and forward adjustment on the carriage, a corner-lap disc shaft in the front carrier geared to operate with the driving shaft and journaled in the front carrier, a second 45 corner-lap disc shaft journaled in the rear carrier having sliding gear connection with the driving shaft, a side carrier adapted to lateral adjustment, a splined corner-lap disc slidably mounted upon the disc shaft of the 50 front carrier, a corner-lap disc splined to the disc shaft of the rear carrier, a housing for each disc adapted to move along the disc shaft and a longitudinally slidable connection between the rearward housing and the side carrier. 55
52. A stationary front carrier, a rearward and forwardly adjustable rear carrier, a side carrier, a pinion, parallel racks meshing with 60 the pinion upon opposite sides thereof and respectively rigid and slidable with the side carrier, a rod carried by the side carrier slidably supporting the slidable rack, a housing slid- 65 able on the slidable rack and carrying and positioned by the pinion, a connection between the rear carrier and slidable rack, and a side brush carried on the housing of the pinion.
53. A side carrier, a pinion, parallel racks meshing with the pinion upon opposite sides thereof and respectively rigidly fastened to the carrier and adapted to slide along the carrier, a housing carrying and positioned by the pinion, a rear carrier forwardly and rearwardly adjustable and connected to the slid- 70 able rack and a side brush mounted on the housing. 75
54. A side carrier, a pinion, parallel racks meshing with the pinion upon opposite sides thereof and respectively rigidly fastened to the carrier and adapted to slide along the carrier, a housing carrying and positioned by the pinion, a rear carrier forwardly and rearwardly adjustable and connected to the slid- 80 able rack, a side roll, a roll housing supporting the side roll, a laterally slidable supporting connection between the housing and the side carrier and a spring carried by the pinion housing upon each side of the pinion spring-pressing the roll housing away from 85 the side carrier. 90
55. A front or rear carrier having a longitudinal abutment, a corner-lap disc shaft journaled on the carrier, a corner-lap disc splined on the shaft and a housing for the disc positioning the disc along the shaft and having a tongue slidably engaging the abutment to prevent angular deflection of the housing. 95
56. A rear carrier, a corner-lap disc shaft having journal support on the carrier, a corner-lap disc splined upon the shaft, a housing for the disc adapted to position the disc along the shaft, a side carrier adapted to lateral adjustment, a slide upon the side carrier adapted to slide rearwardly and forwardly therealong and a laterally resilient connection between the housing and the slide. 100
57. A turn-in driving shaft, an eccentric mounted thereon having a longitudinally bored arm, a rod extending into the bore of the arm having a head at its inner end and adapted to longitudinal movement within the bore, an inwardly directed flange at the outer end of the arm fitting against the rod, a spring compressed between the head of the rod and the flange spring-pressing the rod inwardly with respect to the arm, a turn-in clamp and operative connection therebetween and the rod. 110
58. A turn-in hook adapted to engage the inside of a box, a rotatable shaft eccentrically journaling an inner end of the hook, a housing to the shaft, a pressure foot rigidly connected to the housing and adapted to engage the outside rim of a box, a link support between the foot and turn-in hook and mechanism for resiliently operating the shaft. 115
59. In box wrapping mechanism a carriage, a frame structure within which the carriage is adapted to reciprocate, a carrier sup- 120
- 60 the pinion upon opposite sides thereof and respectively rigid and slidable with the side carrier, a rod carried by the side carrier slidably supporting the slidable rack, a housing slid- 65 able on the slidable rack and carrying and positioned by the pinion, a connection between the rear carrier and slidable rack, and a side brush carried on the housing of the pinion. 70

- porting side wrapping and turn-in mechanism, a turn-in hook adapted to engage the inside of a box, a rotatable shaft eccentrically journaling the inner end of the hook, a housing for the shaft rigidly supported by the carrier, a pressure foot rigidly connected to the housing and adapted to engage the outside rim of the box, a link support between the foot and the turn-in hook, a turn-in driving shaft carried by the carriage and operatively connected to the first shaft, a guideway carried by the side of the frame structure, a bell crank geared to the turn-in driving shaft having pivoted support upon the carriage and operating connection with the guideway adapted to oscillate the turn-in driving shaft by the reciprocation of the carriage. 70
60. A carriage, a frame structure within which the carriage is adapted to vertically reciprocate, front and rear and side carriers on the carriage supporting side wrapping mechanism, a shaft journaling in the carriage, a pinion on the end of the shaft, a toothed sector meshing with the pinion and 75
- 20 pivotedly mounted on the carriage, an arm rigidly carried by the sector, a cam member having a cam slot adapted to guide the arm to oscillate the segment by the reciprocation of the carriage eccentric pivotal supports between the cam and the frame structure adapting the cam to curved movement transverse to the length of its slot, a turn-in hook adapted to engage the inside of the box, a pressure foot adapted to engage the outside of a box 80
- 25 to support the clamping action of the hook, operating connection between the shaft and the hook, a face cam carried upon the shaft, a cooperating cam member spring-pressed toward engagement with the face cam and 85
- 30 adapted to slide along the shaft, means for preventing angular motion of the cooperating cam member upon the shaft, box-support rods mounted upon the cooperating cam member and timed means for oscillating the vertical cam to operate the support rods. 90
61. A carriage, a frame structure in which the carriage is adapted to reciprocate, a driving shaft adapted to reciprocate the carriage, a rear carrier adapted to forward and rearward adjustment upon the carriage, a shaft journaling in the carriage transversely to the rear carrier and along which the rear carrier is adapted to slide, an eccentric splined upon the shaft and housed in the rear carrier and 95
- 50 rear turn-in mechanism supported upon the back of the carrier operated by the eccentric, and connections for oscillating the shaft during the reciprocating movement of the carriage. 100
60. 62. A carrier, an upper and lower two-part housing mounted upon the back thereof, a two-part rack member comprising an upper portion and a sleeve rack lower portion, a gear meshing with the rack and housed in 105 the lower portion of the housing, a turn-in having crank connection with the gear, a pressure foot rigidly fastened to the lower part housing, link support between the pressure foot and the turn-in, rocker arm mechanism carried by the carrier for reciprocating the rack and having operative connection to the upper part of the rack member, latch connection between the parts of the rack member, and other latch connection between the parts of the housing. 110
5. 63. A carrier, a rack member having a lateral recess and housed on the carrier for turn-in operation, a slotted pin pivotally mounted transversely in the recess of the rack member, a bell crank pivotally mounted on the carrier and having an arm operatively connected in the slot of the pin and means for rocking the bell crank to effect the operation of the turn-in. 115
64. A turn-in hook adapted to engage the inside rim of a box and having a downward extension, a crank shaft, crank connection between the hook and the shaft, a housing for the shaft a pressure foot rigidly connected to the housing and adapted to engage the outside of a box, a link support between the pressure foot and the downward extension of the hook cooperating with the crank to guide the turn-in hook and means for operating the shaft. 120
65. A carriage, a frame structure within which the carriage is adapted to vertically reciprocate, a driving shaft journaled in the frame structure, a crank upon the driving shaft, operating connection between the crank and carriage adapting the rotary motion of the shaft to vertically reciprocate the carriage, and an offsetting adjustment of the crank. 125
66. In side wrapping turn-in mechanism, a carriage, a driving shaft, crank connection between the driving shaft and the carriage for vertically reciprocating the carriage, frame structure within which the carriage is adapted to reciprocate, turn-ins carried by the carriage, a cam fastened to the side of the frame structure, operative connection between the cam and the turn-ins, vertically adjustable box support rods carried by the carriage and an offsetting adjustment of the crank. 130
67. A carriage, frame structure within which the carriage is adapted to reciprocate, a rocker shaft, a rocker arm mounted therein, link connection between the rocker arm and carriage, a carriage supporting rod pivoted at its upper end to the arm and having sliding pivot connection with the frame structure at its lower end and placed angularly with respect to the rocker shaft so that when the carriage is in low position the rod makes an obtuse angle with the rocker arm, and a spring compressed between the upper and lower pivots of the rod for supporting the weight of the carriage. 135
68. Wrap feeding mechanism, an intermit- 140

tent turret carrying box forms forwardly slotted, a trip lever having a toe adapted to register with the slots in the forms or to engage the bottom of a box if the slot is covered by a box carried on the form, a spring mounted 5 near its dead center to spring-press the toe upon one side of the dead center to maintain the toe in its engagement position and upon deflection of the toe by its engagement with a box to press on the other side of its dead center to move the toe away from engagement position, means operating by the rocking of the toe from its engagement position with the box to shut down the feed mechanism and other means for returning the toe to position 15 for box engagement before the next form reaches it.

69. A turret carrying recessed box forms, wrap applying mechanism adapted to apply a wrap to the bottom of a box carried on one of the forms, a trip lever having a toe adapted to register with the recesses on the box forms or to engage a box carried upon the form, frame supporting structure, a stud thereon, inner 20 and outer gears pivotally mounted hub by hub on the stud, a pin and socket clutch connection between the gears comprising a pin slidably mounted in the hub of the inner gear, adapted to register with a socket in the adjacent face of the hub of the outer gear and to 25 rearward movement into the hub of the inner gear to release the clutch, a spring pressing the pin toward the outer gear, rack teeth on the pin, a pinion meshing with the rack teeth 30 and pivoted in the hub of the inner gear, a rack slidably in the hub of the inner gear, meshing with the other side of the pinion and having an end for operating the pin adapted to project from beyond the inner face of the 35 hub, a movable cam carried on the frame structure in the path of the projecting end of the rack and adapted to press back the rack to release the clutch before the engagement between the wrap-applying mechanism and 40 any one of the forms, mechanism operative by the trip lever for moving the cam out of the path of the end of the rack to prevent operation of the clutch when a box is upon a form and other mechanism for returning the 45 cam to its shut down position before the registry of the trip lever with the recess of the next form or before its engagement with the box on the next form if a box is present.

70. In turn-in mechanism, a turn-in hook 55 adapted to engage the inside of a box, a rotatable shaft eccentrically journaling an inner end of the hook, a housing for the shaft, a presser foot rigidly connected to the housing and adapted to engage the outside rim of a 60 box, a link support and connection between the foot and the turn-in hook, and operating means for the shaft.

71. In turn-in mechanism for operating on boxes of variant length, a turn-in clamp member, a crank shaft having crank connection 65

to one end thereof, a housing for the shaft, a presser foot clamp member cooperating with the hook member and rigid with the housing, link connection between the turn-in member and the presser foot cooperating with the crank connection to guide the turn-in, a removable angle box-engaging member fastened to the hook member of length to fit a box, and means to oscillate the shaft. 70

72. A pinion, a housing therefor journaling the teeth of the pinion, crank pins in each end of the pinion, a hook turn-in member having one end mounted on the crank pins, a downward extension on the turn-in member, a presser foot rigid with the housing, a downwardly extending link connected at its upper end to the foot and at its lower end to the extension, and a rack meshing with the pinion, a housing therefor and mechanism for reciprocating the rack within its housing to operate the turn-in clamp. 75

73. A carrier, a housing mounted upon the back thereof, a rack member adapted to reciprocate in the housing, a gear meshing with the rack, a turn-in having crank connection with the gear, a presser foot rigidly fastened to the housing, link support between the presser foot and the turn-in, and rocker arm mechanism for reciprocating the rack. 80

74. A carrier, a rocker arm mounted thereon, a housing mounted on the back of the carrier, a rack member adapted to reciprocate in the housing, a pinion meshing with the rack and having bearing support in the housing, a turn-in member having crank connection with the pinion, a presser foot rigidly connected to the housing, link connection between the turn-in and the presser foot cooperating with the crank to position the turn-in, a pin adapted to turn in the upper end of the rack and slotted to receive one arm of the rocker and eccentric means for rocking the rocker. 100

75. In an automatic wrapping mechanism, a carriage for side wrapping mechanism comprising end plates, front and rear tie-rods therebetween upon opposite sides thereof, a front carrier rigidly connected between the ends, side carriers supported upon and adjustable along the tie-rods, and a rear carrier having a forward and rearward adjustment. 110

76. A turret having successive periods of rest and dwell and adapted to carry box forms for presentation of boxes to side wrapping mechanism, side wrapping mechanism adapted to reciprocate to operate successively upon boxes presented by the forms during successive periods of dwell of the turret, and registry mechanism for exactly registering the turret in presentation position during each period of dwell. 120

77. In a box wrapping machine, side wrapping mechanism adapted to pass over the sides of a box, an intermittent turret carrying 125

a box form and adapted to present the form in dwell in registered position adjacent the side wrapping mechanism and a box gripper operated to hold a box to the form as it approaches the dwell and to move out of the way of the advancing side wrapping mechanism.

5. 78. A box wrapping machine and an intermittent turret having arms forwardly offset from the turret axis and box forms removably fastened at their forward ends to the outer ends of the arms.

10. 79. In the art of wrapping the bottoms, sides and ends of a wrap upon the outside 15 of a box, the method which consists in moving the box intermittently, in registering the initial positions of the boxes with respect to the forward ends of the boxes, in applying the wraps to the boxes at the forward edges 20 of the forward ends and in registering the other operations upon the box likewise with respect to the forward edge of the box.

25. 80. In a box wrapping machine, a gluing roll, a wrap supporting roll adapted to receive successive wraps from the gluing roll, holding mechanism for the boxes to which the wraps are to be successively applied and other mechanism for delivering the wrap bodily from the gluing roll to the wrap supporting roll and then moving the wrap supporting roll bodily for wrap delivery to a 30 box on the holding mechanism.

35. 81. In a box wrapping machine, a wrap applying roll having bodily different positions, means for delivering a glued wrap bodily to the applying roll while the applying roll is in one position, box holding means spaced from one position of the applying roll and mechanism operative after a glued wrap 40 has been delivered bodily to the applying roll for shifting the applying roll bodily into engagement with a bottom edge of a box on the holding mechanism, and other means for bodily moving the box so that the full length 45 of the bottom of the box is engaged by the roll.

WALTER A. SAATMAN.
